Brian Leonard Wilcox, Birmingham, England, assignor to
Dunlop Limited, Birmingham, England

Filed July 16, 1971, Ser. No. 163,563

Claims priority, application Great Britain Jan. 21, 1971

Term of patent 14 years

Int. Cl. D12—15

U.S. Cl. D90—20

FIG. I.

Des 225,915

PAGE 2

FIG.2.

FIG. 3.

FIG. 1 is a full perspective view of a tire showing my new design;

FIG. 2 is a front perspective view of the tire;

FIG. 3 is a side view of the tire.

Both sidewalls are the same.

I claim:

The ornamental design for a tire, as shown and described.
